US00D927282S

(12) **United States Design Patent** (10) **Patent No.:** **US D927,282 S**
(45) **Date of Patent:** **** Aug. 10, 2021**

(54) **DOOR HANDLE**

(71) Applicant: **TONG LUNG METAL INDUSTRY CO., LTD.**, Chiayi County (TW)

(72) Inventors: **Mei-Ching Chu**, Chiayi (TW); **Suh-You Yang**, Chiayi (TW); **Shih-Kai Hsu**, Chiayi (TW)

(73) Assignee: **TONG LUNG METAL INDUSTRY CO., LTD.**, Chiayi County (TW)

(**) Term: **15 Years**

(21) Appl. No.: **29/688,091**

(22) Filed: **Apr. 18, 2019**

(30) **Foreign Application Priority Data**

Nov. 14, 2018 (TW) 107306681

(51) **LOC (13) Cl.** **08-06**

(52) **U.S. Cl.**

(57) **CLAIM**

The ornamental design for a door handle, as shown and described.

DESCRIPTION

FIG. 1 is a perspective view of a door handle showing my new design;

FIG. 2 is a front elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The rear elevational view is not part of the claimed design and is not shown.

(Continued)

The broken lines depict portions of a door handle in which the design is embodied that represent unclaimed subject matter and form no part of the claimed design.

1 Claim, 4 Drawing Sheets
